J. B. HENDERSON
SIGHT FOR GUNS, BOMB DROPPERS, AND THE LIKE FOR USE ON
SHIPS AND OTHER MOVING PLATFORMS
Original Filed July 26, 1919

UNITED STATES PATENT OFFICE.

JAMES BLACKLOCK HENDERSON, OF LEE, ENGLAND.

SIGHT FOR GUNS, BOMB DROPPERS, AND THE LIKE FOR USE ON SHIPS AND OTHER MOVING PLATFORMS.

Original application filed July 26, 1919, Serial No. 313,541, and in England August 4, 1916. Divided and this application filed July 26, 1920. Serial No. 229,608.

My invention consists in improvements in gun-sights, bomb-sights and the like, for use on board ship or on other moving platforms, whereby those effects on the trajectory are compensated which are produced by the angular motion of the ship around the line of sight to the target. For example, if a gun be trained fore and aft in a ship and be elevated at an angle α for range R , then if the ship rolls with amplitude θ and the gun-sight be kept always trained on the target, the vertical plane through the axis of the gun, which is approximately the plane of the trajectory, oscillates in azimuth on both sides of the target with an amplitude $\tan \alpha \sin \theta$ and the elevation of the gun varies from α to $\alpha + \cosine \theta$ with double the frequency of roll. Thus at a range of 15,000 yards with a 12" gun, if the ship were rolling 10 degrees on either side of the vertical, the deflection of the shot might amount to ± 600 yards and the error in range might amount to ± 130 yards.

Various devices have been already proposed to correct this error, and serve to position the sighting line in a vertical plane parallel to the axis of the gun, and inclined at an angle relatively to the axis of the gun in this vertical plane.

The present application is a divisional one from my copending United States application No. 313,541.

According to my invention I compensate the error in the trajectory by causing the line of collimation of the sighting telescope or the like to be moved in azimuth and in elevation relatively to the ship by the angular motion around the line of sight causing a relative displacement of the image of the target and the cross wires of the telescope, the said relative displacement being effected in whole or in part by a gyroscope, the displacement being produced either automatically by the gyroscope or by hand through the intervention of a follow the pointer mechanism, the pointer of which is controlled by the gyroscope. In every case the line of collimation is maintained parallel to the plane of the trajectory.

Fig. 1 is an elevation, partly in section of an arrangement of gyroscopic telescope in which the gyroscope produces automatically the deflection of the line of collimation required.

Fig. 2 is a transverse sectional view approximately along the line 2-2 of Fig. 1.

Fig. 3 shows a cross section of the telescope corresponding to Fig. 2 but illustrating the follow the pointer mechanism.

In Figs. 1 and 2 the telescope case 1 is supported on trunnions 2 and 3 on the frame 4, the elevating motion about the trunnions being introduced by the screw 4^a and fixed nut 4^b. The sighting telescope consists of the variable power erecting eye-piece 5, the single reflecting prism 6, objective in its holder 7 and the mirror 8 mounted by trunnions 9, 9 within the case 1. A gyroscope 10 with its rotor axis controlled approximately vertical by gravitational means is mounted by trunnions 16, 16 within a ring 11 which is mounted by suitable trunnions within the case 1. Associated with the mirror 8 is a pulley 12 having twice the diameter of a pulley 13 on one of the trunnions of ring 11. The pulleys are connected by a belt 11^a, so that one half of the relative movement between pulley 13 which is stabilized by the gyroscope and the case which partakes of the angular movement of the platform is communicated to pulley 12. The mirror 8 therefore moves relatively to the case 1 through an angle equal to one half of that through which the case moves with the platform. An image of a distant object is accordingly maintained in the field of view of the telescope to compensate for movement of the platform about an axis perpendicular to a vertical plane containing the line of sight to the object.

In order to apply my present invention to this instrument I turn the prism 6 round a vertical axis thereby displacing the image of the target relatively to the cross wires and I arrange this displacement to be brought about by the gyroscope automatically or by hand as the ship rolls and of such a magnitude that the error in training in question is correctly compensated. The prism 6 is mounted on a vertical trunnion 14 turning in a sleeve 14^a attached to the bracket 14^b which is fixed to the casing 1. The prism is turned about the trunnion 14 by a crank 15 which is moved by the tilting of the gyroscope 10 about the trunnion axis 16. This tilt is transmitted by the link 17 to the rocking lever 18, thence through the hollow trunnion of the gimbal ring by

means of the link 19 to the rocking lever 20, the right end of the link 19 being supported by the link 20^a from the case of the instrument.

5 The rocking lever 20 is pivoted on the case of the instrument upon an adjustable pivot 21 which engages with a slot 21^a in the lever 20. The lever 20 is connected with the crank 15 which turns the prism 6 by a link 22 10 which has a ball joint at each end. The fulcrum 21 about which the lever 20 turns is adjustable up and down by means of the screw 23 (Fig. 1) which is turned by the head 24 and is threaded through the movable slide 25 which carries the bracket 21^b and the fulcrum 21. The position of the fulcrum is indicated by a scale on the disc 26 15 which is turned by the pinion 27 attached to the head 24. This scale may be graduated in degrees of elevation of the gun or in ranges, the pointer 28 indicating the appropriate setting of the fulcrum 21.

It is evident from the arrangement of the mechanism that any tilting of the trunnions 25 2-3 relatively to the gyro trunnion 14 will produce, when the gyroscope is acting, a lateral motion of the links 17 and 19 causing the link 20 to turn about its fulcrum 21 and transmitting through the connecting rod 22 to the crank 15 an angular displacement about the trunnion 14, thus turning the prism 6 in azimuth and displacing the image of the target horizontally in the field of view of the telescope. The ratios of the links are so arranged that this displacement is just sufficient to compensate the error in the trajectory which would otherwise be produced by the tilting of the trunnion axis 2-3.

40 Fig. 3 shows the arrangement which I may use when I desire to give the gyroscope as little work to do as possible. The upper end of the lever 20 is connected to a push rod 30, the handle of which projects outside the case 1. This handle is manipulated by a second observer who keeps the pointer 31, which is attached to the rod 30, in line with the pointer 32 which is attached to the gyro case. The fulcrum 21 is in this case 45 above the crank 15 instead of below it as in Fig. 2, but the bracket 21^b which carries the fulcrum 21 is attached to the slide 25 as before and moves up and down with it.

Having now particularly described and ascertained the nature of my said invention and in what manner the same is to be performed, I declare that what I claim is:—

1. In apparatus for sighting a projectile discharging device mounted on an angularly moving platform, a member adapted normally to bear a predetermined relation to the line of sight, a gyroscope, means associated with the gyroscope whereby the relation of the member to the line of sight may be changed 60 in accordance with the angular movement of

the platform and means associated with said means for controlling the change in the relation of the member in accordance with the range adjustment of the device.

2. In apparatus for sighting a projectile discharging device mounted on an angularly moving platform, a member adapted normally to bear a predetermined relation to the line of sight, a gyroscope, connections between the member and the gyroscope for changing the relation of the member to the line of sight in accordance with the angular movement of the platform and means associated with the connections for controlling the change in the relation of the member in accordance with the range adjustment of the device.

3. In apparatus for sighting a projectile discharging device mounted on an angularly moving platform, a telescope, means associated with the telescope for viewing a distant object, a gyroscope, connections between the viewing means and the gyroscope for moving the former to displace the image of the object in the field of the telescope in accordance with the angular movement of the platform and means associated with the connections for controlling the movement imparted to the viewing means in accordance with the range adjustment of the device.

4. In a sighting apparatus for a projectile discharging device mounted upon an angularly moving platform, an optical device for viewing a distant object, an element adjustable in accordance with the range adjustments of the device, first a gyroscope, a member connected to said element and adapted to be maintained in a predetermined relation to the gyroscope, and means actuated by the member for producing a displacement of the optical device to compensate for the effect of the movement of the platform upon the trajectory of the projectile.

5. In a sighting apparatus for a projectile discharging device mounted upon an angularly moving platform, a member adapted normally to bear a predetermined relation to the line of sight, an element adjustable in accordance with the range adjustments of the device, a gyroscope, a member connected to said element and adapted to be maintained in a predetermined relation to the gyroscope, and means actuated by the second named member for changing the relation of the first named member to the line of sight in accordance with the angular movement of the platform to compensate for the effect of the movement of the platform upon the trajectory of the projectile.

6. In a sighting apparatus for a projectile discharging device mounted upon an angularly moving platform, a member adapted normally to bear a predetermined relation to the line of sight, an element adjustable in accordance with the range adjustments of the

- device, a gyroscope, a pointer associated therewith, a member connected to said element and adapted to be maintained in a predetermined relation to the pointer, and means actuated by the second named member for changing the relation of the first named member to the line of sight in accordance with the angular movement of the platform to compensate for the effect of the movement of the platform upon the trajectory of the projectile. 75
7. In a sighting apparatus for a projectile discharging device mounted upon an angularly moving platform, an optical device for viewing a distant object, an element adjustable in accordance with the range adjustments of the device, a gyroscope, a pointer associated therewith, a member connected to said element and adapted to be maintained in a predetermined relation to the pointer, and means actuated by the member for producing displacement of the optical device to compensate for the effect of the movement of the platform upon the trajectory of the projectile. 80
8. In a sighting apparatus for a projectile discharging device mounted upon an angularly moving platform, a member adapted normally to bear a predetermined relation to the line of sight, a gyroscope, mechanism comprising a part adjustable in accordance with the angle of gun elevation and a part connected to the member, and means connected to the mechanism and adapted to be maintained in a predetermined relation to the gyroscope for moving the mechanism to change the relation of the member to the line of sight in accordance with functions of the elevation of the device and the angular movement of the platform. 85
9. Apparatus for correcting for the effect of the angular movement of a platform upon a projectile discharging device mounted thereon, comprising a member adapted normally to bear a predetermined relation to the line of sight, a gyroscope, a member adapted to be maintained in a predetermined relation to the gyroscope, a member connected to the second named member and adjustable in accordance with the angle of elevation of the device, and means connecting the first and second members for changing the relation of the first member to the line of sight in accordance with functions of the elevation of the device and the angular movement of the platform as the second member is maintained in predetermined relation to the gyroscope. 90
10. Apparatus for correcting for the effect of the angular movement of a platform upon a projectile discharging device mounted thereon, comprising a sighting instrument, a gyroscope, a member adapted to be maintained in a predetermined relation to the gyroscope, a member connected to the second member and adjustable in accordance with the range adjustment of the device, and means actuated by the first named member for shifting the line of collimation of the instrument in accordance with functions of the elevation of the gun and the angular movement of the platform as the first named member is maintained in predetermined relation to the gyroscope. 100
11. Apparatus for sighting a gun mounted on an angularly moving platform, comprising a telescope, means for moving the line of collimation of the telescope, a gyroscope and an indicating means including a part associated with the gyroscope and a part associated with the first named means whereby the line of collimation of the telescope may be moved in accordance with the angular motion of the gun around the line of sight. 105
12. Apparatus for sighting a gun mounted on an angularly moving platform, comprising a sighting instrument, a member movable in accordance with the elevation of the gun measured from a predetermined plane, a member adapted to be maintained in a predetermined relation to the instrument, a gyroscope, an indicator comprising a part associated with the gyroscope and a part associated with the first named member, and means connecting the last named part and the second named member for moving the latter to displace the line of collimation of the sighting instrument in accordance with a function of the angular movement of the platform and the elevation of the gun. 110
13. Apparatus for sighting a gun mounted on an angularly moving platform, comprising an optical instrument and gyroscopically controlled means for maintaining the line of collimation of the telescope parallel to a vertical plane through the axis of the gun and depressed in said plane at a constant angle below the axis of the gun. 115
14. In sighting apparatus for a projectile discharging device mounted upon an angularly moving platform, a gyroscope, means controlled by the gyroscope for compensating for the effect on the field of view of the apparatus of movement of the platform about an axis perpendicular to a vertical plane containing the line of sight to a distant object and means associated with the gyroscope whereby compensation may be made for the effect on the device of movement of the platform about an axis parallel to the line of sight. 120
15. In sighting apparatus for a projectile discharging device mounted upon an angularly moving platform, a gyroscope, means controlled by the gyroscope for compensating for the effect on the field of view of the apparatus of movement of the platform about an axis perpendicular to a vertical plane containing the line of sight to a distant object, a member adapted normally to 125

bear a predetermined relation to the line of sight, means associated with the gyroscope whereby the relation of the member to the line of sight may be changed in accordance with the movement of the platform about an axis parallel to the line of sight and means associated with said means for controlling the change in the relation of the member in accordance with the range adjustment of the device.

16. In sighting apparatus for a projectile discharging device mounted upon an angularly moving platform, an optical element by which a distant object may be viewed, a gyroscope, means controlled by the gyroscope for actuating the element to compensate for the angular movement of the platform about an axis perpendicular to a vertical plane containing the line of sight, a second optical element for use in conjunction with the first optical element for viewing the object and means associated with the gyroscope whereby the second optical element may be actuated to compensate for the effect on the device of movement of the platform about an axis parallel to the line of sight.

17. In sighting apparatus for a projec-

tile discharging device mounted upon an angularly moving platform, a telescope, gyroscopically controlled means for maintaining the image of a distant object fixed in the field of view of the telescope and means associated with the first named means whereby compensation may be made for the effect on the device of movement of the platform about an axis parallel to the line of sight.

18. In sighting apparatus for a projectile discharging device mounted upon an angularly moving platform, a pair of optical elements by which a distant object may be viewed, a gyroscope, means for actuating one of the elements to compensate for the effect on the field of view of the apparatus of movement of the platform about an axis perpendicular to a vertical plane containing the line of sight and means associated with the gyroscope whereby the other optical element may be actuated to compensate for the effect on the device of movement of the platform about an axis parallel to the line of sight.

JAMES BLACKLOCK HENDERSON.

bear a predetermined relation to the line of sight, means associated with the gyroscope whereby the relation of the member to the line of sight may be changed in accordance with the movement of the platform about an axis parallel to the line of sight and means associated with said means for controlling the change in the relation of the member in accordance with the range adjustment of the device.

16. In sighting apparatus for a projectile discharging device mounted upon an angularly moving platform, an optical element by which a distant object may be viewed, a gyroscope, means controlled by the gyroscope for actuating the element to compensate for the angular movement of the platform about an axis perpendicular to a vertical plane containing the line of sight, a second optical element for use in conjunction with the first optical element for viewing the object and means associated with the gyroscope whereby the second optical element may be actuated to compensate for the effect on the device of movement of the platform about an axis parallel to the line of sight.

17. In sighting apparatus for a projec-

tile discharging device mounted upon an angularly moving platform, a telescope, gyroscopically controlled means for maintaining the image of a distant object fixed in the field of view of the telescope and means associated with the first named means whereby compensation may be made for the effect on the device of movement of the platform about an axis parallel to the line of sight.

18. In sighting apparatus for a projectile discharging device mounted upon an angularly moving platform, a pair of optical elements by which a distant object may be viewed, a gyroscope, means for actuating one of the elements to compensate for the effect on the field of view of the apparatus of movement of the platform about an axis perpendicular to a vertical plane containing the line of sight and means associated with the gyroscope whereby the other optical element may be actuated to compensate for the effect on the device of movement of the platform about an axis parallel to the line of sight.

JAMES BLACKLOCK HENDERSON.

Certificate of Correction.

It is hereby certified that in Letters Patent No. 1,588,682, granted June 15, 1926, upon the application of James Blacklock Henderson, of Lee, England, for an improvement in "Sights for Guns, Bomb Droppers, and the Like for Use on Ships and Other Moving Platforms," an error appears in the printed specification requiring correction as follows: Page 2, line 101, claim 4, strike out the word "first" and insert the same before the word "device" in same line; and that the said Letters Patent should be read with this correction therein that the same may conform to the record of the case in the Patent Office.

Signed and sealed this 3d day of August, A. D. 1926.

[SEAL.]
